UNITED STATES PATENT OFFICE.

WILLIAM ALBRECHT, OF ST. JOSEPH, MISSOURI, ASSIGNOR TO WESTERN TABLET & STATIONERY COMPANY, OF ST. JOSEPH, MISSOURI, A CORPORATION OF MISSOURI

STUDENT'S WORK CONTAINER.

Application filed February 29, 1924. Serial No. 696,077.

To all whom it may concern:

Be it known that I, WILLIAM ALBRECHT, a citizen of the United States, residing at St. Joseph, in the county of Buchanan and State of Missouri, have invented certain new and useful Improvements in Students' Work Containers, of which the following is a specification.

This invention relates to certain new and useful improvements in student's work container and it has for its objects to provide a cover which will make it possible for each student to have his work and equipment always at hand and always in good order; to provide a container which is handy, practical, convenient, one in which the writing matter may be arranged in a convenient manner, ready for immediate use, one the use of which will systematize the writing supplies so as to insure orderly arranged desks, one which will enable the pupils to carry home all their writing supplies, etc., and one which provides a convenient place to file manuscripts and other school papers.

Again it is an object of the invention to provide means for removing the ever present danger of accident when sharp pointed pens, pencils, compasses, etc., are carried in the hand or pocket, and to provide means by the use of which those supplies which the student uses continuously may not become lost or misplaced.

With other objects in view which will be clear to those skilled in the art, the invention also includes those novel features of construction, combination and arrangement of parts, all of which will be first fully described, then be specifically pointed out in the appended claims, reference being had to the accompanying drawings, in which:

Figure 1 is a perspective view of my invention by itself.

Figure 2 is a similar view showing the container provided with tablets, manuscripts, papers, pens, pencils, compasses, etc., and arranged in the manner of use of the same.

Figure 3 is a diagrammatic view of the blank from which the container is made.

Figure 4 is a vertical section on the line 4-4 of Figure 2.

Figure 5 is a horizontal section on the line 5-5 of Figure 2.

Figure 6 is a horizontal section on the line 6-6 of Figure 2.

Referring now to the accompanying drawings in which like numerals of reference designate like parts in all the figures, 1 and 2 represent the cover portions of the container which are connected to the back 3 by hinge joints 4-4; the parts 1, 2 and 3 may be formed integrally and the hinge joints 4 may be formed by scoring and folding the parts along the dotted line shown in Figure 3.

Projected from the lower edge of the front cover 1 is an extension 5 of a length less than the length of the cover 1, the extension 5 being provided with ears or laterally extending parts 6-6, the latter being adapted to be folded over, as at 9, to lie between the opposing faces of the cover 1 and extension 5 when the extension 5 is folded up at 7, see Figure 1. In order to secure the extension 5 in position to form a pocket on the inner side of the cover 1, rivets 10 are provided to fasten the ears 6 to the cover 1, and in order to permit the rivets being placed, the extension 5 has openings or windows 8 to expose the rivets.

From the lower edge of the back cover 2 another extension 11 is provided which also has ears 12 extending laterally and adapted to be folded over, as at 16, to lie between the opposing faces of the extension 11 and the cover 2 when the extension 11 is folded over at 13 against the cover 2. In order to secure the ears 12 to the cover 2 and hold the extension 11 in a pocket forming position, rivets 15 are provided which pass through the ears 12 and the cover 2, and in order to permit placing these rivets 15 the extension 11 has openings or windows 14 in register therewith.

17 designates a corrugated metal band having flat ends 18 secured by the rivets 15 and placed within the pocket formed by the extension 11 and cover 2 and constituting a pencil and other implement holder or clip, the corrugated body 17 having a flat portion 19 to engage the face of the pocket forming extension 11, it being understood that the holder 17 is somewhat resilient so as to hold the pens, pencils, etc., by retaining friction against the opposing face of the extension 11.

In the manufacture of my container the same may be made of any suitable material, for instance jute lined container board, metal, leather, fibre, cloth, cardboard, or 5 other suitable material.

It will be noted from the foregoing description, taken in connection with the accompanying drawings, that by the use of my invention the bindings of expensive text 10 books are saved for the reason that the student no longer will have to use these text books as "carry alls" for carrying their supplies to different classes. The danger of 15 breaking the backs or bindings of the text books is thus avoided.

From the foregoing description, taken in connection with the accompanying drawings, it is thought the construction and advantages of my invention will be clear to 20 those skilled in the art.

What I claim is:

1. A student's work container comprising two covers hinged to a back in foldable book fashion, and an extension from the

bottom edge of each cover folded along said bottom edge back upon the inner faces of the respective covers, each of said extensions having lateral flaps folded under the same and secured to the covers to constitute pockets, and means for securing said flaps 25 to the covers, said extensions having openings to permit access to said securing means.

2. A student's work container comprising a pair of covers hingedly united by a back in foldable book fashion, each of said covers 30 having extensions along the bottom edges folded back upon the covers on the inside of the same and having ears folded back under the extensions and securing to the covers, said extensions and covers thereby 35 constituting pockets, and a corrugated implement holder secured in one pocket, said extension having openings, and securing means passing through said covers and ears 40 in register with said openings to sustain 45 the parts in position.

WILLIAM ALBRECHT.
